United States Patent Office

Des. 205,319
Patented July 19, 1966

205,319

REFUSE RECEPTACLE

Max Klein, 8915 Northend Ave., Detroit, Mich.

Filed Apr. 28, 1965, Ser. No. 85,003

Term of patent 14 years

(Cl. D58—17)

FIG. 1

FIG. 2

FIG. 3

FIG. 4

FIG. 5

FIG. 6

FIG. 7

FIG. 8

FIG. 1 is a perspective view of a refuse receptacle showing my new design;

FIG. 2 is a side elevational view;

FIG. 3 is a bottom plan view;

FIG. 4 is a fragmentary bottom perspective view;

FIG. 5 is a perspective view on a slightly reduced scale looking from the right of FIG. 2;

FIG. 6 is a perspective view looking from the left of, and in the same scale as, FIG. 2;

FIG. 7 is a top plan view; and

FIG. 8 is a top perspective view thereof on an enlarged scale with the cover removed.

I claim:

The ornamental design for a refuse receptacle, substantially as shown.
